UNITED STATES PATENT OFFICE.

ALBERT K. WAYCOTT, OF LARCHMONT, NEW YORK.

STEAM AND WATER VALVE.

Application filed December 30, 1920. Serial No. 434,036.

To all whom it may concern:

Be it known that I, ALBERT K. WAYCOTT, a citizen of the United States, residing in the village of Larchmont, county of Westchester, and State of New York, have invented a new and useful Improvement in a Steam and Water Valve, of which the following description, in connection with the accompanying drawings, is a specification, like characters in the drawings representing like parts.

This invention relates to water and steam valves, more particularly of the globe, angle and cross valve variety, and the object of the invention is to provide a valve of this kind having a removable combined liner and plug or gate housing, which can be readily withdrawn for regrinding or replacement, when worn.

It not infrequently becomes necessary to regrind a valve or gate seat, or otherwise repair the plug or gate housing in steam or water valves of the class above referred to, and often in such cases, valves are located in such difficult places of access, or where steam is employed the surroundings are so hot, that the work cannot be done without temporarily discontinuing the use of the connected steam or water pipes, or removing the valve itself.

In such circumstances with the kind of valves now in use, the making of such repairs is laborious, difficult and often times dangerous.

With the use, however, of this invention, it is only necessary to unscrew the bonnet, withdraw the liner, which can be repaired at leisure, insert a new liner in its place, and attach the bonnet, which operation can ordinarily be effected in a few minutes time, and thus obviating the discontinuance of the use of steam or water pipes, for a considerable period, as is customary, under present equipment.

In the accompanying drawing showing an illustrative embodiment of this invention, and in which the same reference numerals refer to similar parts in the several figures, Fig. 1 is a side elevation of a valve of this description, showing the removable body liner and main body assembly in section, the plug, disc or gate being shown at the end of the spindle partially broken away for clearness, Fig. 2 is a horizontal cross sectional view taken on the line 2—2 (Fig. 1), Fig. 3 is an elevational perspective view of the

removable liner, Fig. 4 is a side elevational view of the inner portion of the spindle with a modified plug or gate in section.

In the drawings, the numeral 1 indicates the tapering cylindrical liner, on opposite sides of which are provided openings 5 extending circumferentially, leaving only the portions 7 which connect the upper and lower portions 4 and 3 of the liner, which movably grip and act as guides, for the up and down travel of the plug or gate.

The inside lengthwise bore or surface of the liner 1 is of uniform diameter from the opening at the end 4 to a point at or slightly below the lower edges of the openings 5, where it inclines inwardly, uniformly, circumferentially forming a bevelled seat 6 for the plug or gate 9, and then continues uniformly to the end 3 the opening of which, therefore, is somewhat smaller than the opening at the end 4.

The interior of the body 13 starting at the point 30 and extending downwardly and through the wall 23 is tapered circumferentially, to correspond exactly with the outside surface 2 of the cylindrical liner 1 and adapted to hold or retain it in a horizontal position so that the under surface of the end 3 is flush with the under surface 75 of the wall 23.

When the liner 1 is in place as in Fig. 1, it is removably held in position by the lower end 21 of the bonnet 14, the sides of which end have running circumferentially, an external thread, adapted to play within a similarly internally threaded opening 30 of the body 13, flanged portions 19 of the bonnet adapted for engaging and closing the opening 30.

The spindle 18 has a removable hand wheel 17 at one end and a flange 22 at the opposite end, adapted to be swivelly or movably secured within the plug or gate 9 by means of a threaded lock nut 29 and has a threaded portion 25 adapted to play within a threaded portion of the bonnet 24 for raising and lowering the plug or gate 9 which is of cylindrical formation and adapted to slidably move lengthwise in the liner 1 the sides 28 in contact with the wall of the bore 31 from the opening at the end 4 to the bevelled edge 6 upon which it is adapted to come to rest when the gate is closed.

The gate or plug 9 preferably has bevelled edges, circumferentially at both ends, 10 and 11, the bevelled edge of the lower or

closure end 11, of the same contour as and adapted to fit or seat exactly upon the bevelled edge 6, of the liner 1, and the upper bevelled edge of which 10, of like shape, is 5 adapted to seat and fit within a similar internal bevelled end 8 of the bonnet 14 so that when the valve is opened and the plug or gate 9 has been fully raised by means of the spindle 18, it is fully enmeshed within 10 the end of the bonnet and forms a seal against the escape of water or steam.

The area of each of the openings 5, in the liner 1, is slightly more than the area of the pipe connection openings, 26 and 27, to permit an easy flow of the volume of water or steam.

Escapement of water or steam is prevented by the packing 20, confined by the follower or gland 16, which is held in place 20 by the packing nut 15, the threaded portion of which 12, is screwed to and over the upper end of the bonnet 14.

By swaging the recessed end of the plug or gate 9, as in Fig. 4, allowing some play, 25 a simple method is afforded, of attaching the gate or plug to the end of the spindle.

Having described this invention in connection with the illustrative embodiment thereof to the details of which disclosure the 30 invention is not, of course, to be limited, what is claimed as new and what is desired to be secured by Letters Patent is set forth in the appended claims.

1. A valve having a vertical tapered boring or opening between opposite ports, a 35 tapered liner with side openings therein, adapted for insertion in the boring, internal bevelled annular gate seating means in the smaller end of the liner, in unit there- 40 with, a gate suitable for slidable engagement within the liner, adapted to engage said seating means for closing the liner, a spindle member for turnable connection with the gate means, bonnet means for holding 45 and guiding the spindle means.

2. A valve having a vertical tapered boring or opening between opposite ports, a 50 tapered liner adapted for insertion in the boring, having an opening therethrough lengthwise and two opposite side openings 55 therein, internal annular gate seating means in one end of the liner, a slideable gate for play in the lengthwise opening adapted to engage said seating means for closing the liner, a spindle adapted for turnable connection with the gate member for actuating the same, a bonnet for holding the spindle member.

3. In combination, a valve body member 60 having a vertical tapered boring or opening between opposite ports, a tapered liner adapted for insertion in the valve body boring, having a lengthwise opening there- 65 through and two opposite side openings therein, internal annular gate seating means

in one end of the liner, a gate for cooperating with said seating means for closing the liner adapted for slideable engagement within the lengthwise opening of the liner, a spindle adapted for turnable connection 70 with the gate member for actuating the same, bonnet means for holding the spindle member.

4. In combination, a valve body member having a vertical tapered boring or opening 75 between opposite ports therein, a tapered liner adapted for insertion in the boring, having a lengthwise opening therethrough and two opposite side openings therein, internal annular gate seating means in one 80 end thereof, a gate adapted for seating upon said gate seating means and closing the liner, having a central opening in one end thereof, and swaged around the flanged end of a spindle for movably holding and retaining 85 the same, and a spindle having a flanged end for actuating the gate.

5. In combination, a valve body member, a tapered liner adapted for insertion therein, having a lengthwise opening and two side 90 openings opposite and facing each other, internal gate seating means in the smaller end thereof, a gate adapted to engage said seating means for closing the smaller end of the liner having a recess in one side thereof 95 suitable for receiving the flanged end of a spindle member, and adapted to be reduced annularly by swaging to movably retain and hold the flanged end of the spindle member. 100

6. In combination, a valve body member, a tapered liner adapted for insertion therein, having a lengthwise opening and two side 105 openings opposite and facing each other, internal gate seating means in the smaller end of the liner, a gate adapted to engage said seating means for closing the smaller end of the liner having a recess in one side thereof suitable for receiving the flanged end of a spindle member and swaged around 110 said flanged end to movably retain and hold the same, a spindle member having a flanged end, and a bonnet for guiding the spindle member.

7. A valve having a vertical tapered boring or opening between opposite horizontally placed ports, a tapered liner with end and side openings, adapted for seating in the boring; valve or gate means adapted for closing the smaller end of the liner, a 115 spindle member with annular flanged means at one end for movably engaging the gate means and bonnet means for holding the spindle member.

8. In a valve, the combination with a casting having a vertical tapered boring between opposite ports therein, a removable gate holding member adapted to fit within the vertical boring and having gate seating means at one end, a spindle member, a gate 120

member movably attached thereto adapted to cooperate with said means to hold the gate member at all times in close fitting engagement with its seat in said tapered boring, and bonnet means for holding the spindle member.

9. In a valve, the combination with a casing having a vertical tapered boring between opposite ports therein, a removable gate holding member adapted to fit within the vertical boring and having gate seating means at one end, a spindle member, a gate member movably attached thereto adapted to cooperate with said means to hold

the gate member at all times in close fitting engagement with its seat in said tapered boring and open and close communication between the ports of the casing, and bonnet means for holding the spindle member.

20

In testimony whereof I have signed my name to this specification in the presence of two subscribing witnesses.

ALBERT K. WAYCOTT.
